NICHOLAS A. BECKER, OF PITTSBURG, CALIFORNIA

TOY CHRISTMAS TREE

Application filed January 7, 1930. Serial No. 419,046.

The invention is for a Christmas tree. The objects of the invention are:

First; to provide a small Christmas tree, provided with a plurality of colored electric lamps operable from an ordinary battery 5 similar to an automobile storage battery or dry cells.

Second; to provide a Christmas tree of ornamental design which may be readily attached to any flat, substantially impervious 10 surface and which will be maintained where placed.

Third; to provide a device as described which may be plugged into any convenient 15 receptacle on an automobile and attached to the windshield or other inner surface of said automobile.

Fourth; to provide a device of the class described whereby the branches and trunk of 20 the tree are composed of the connecting wires for the electric lamps, the needles or foliage being retained by two such wires being twisted together with the needles or foliage interposed before twisting.

Fifth; to provide an ornamental device as described which may be economically constructed and on which the lamps can be 25 readily replaced.

Referring to the accompanying drawings: 30 Fig. 1 is an elevation of the invention as mounted on the windshield of an automobile.

Fig. 2 indicates the construction of the individual branches and indicating a lamp mounted on the end thereof.

Fig. 3 is a wiring diagram of the device.

Fig. 4 indicates on a large scale the arrangement of wires and needles and the prongs for attachment of the electric lamps.

Fig. 5 indicates the type of lamp adapted 40 for the prongs in Fig. 4.

Similar reference characters are used to designate similar parts throughout the several views in which:

Reference character 1 indicates the Christ- 45 mas tree in its entirety, which comprises a multiplicity of pairs of insulated wires 2 and 3, each pair forming a branch 4, the wires continuing down through the trunk into the ornamental pot-like member 5 where all 50 positive wires are conductively connected to

one terminal wire 6 and all negative wires conductively connected to the other terminal wire 7, the terminal wires 6 and 7 being of the ordinary two conductor flexible cord type. Conductively attached to the ends of 55 wires 6 and 7, a plug 28 is provided of either single or double contact type to adapt the device for the particular system of wiring of the automobile.

A plurality of branches 4 are provided, 60 each being composed of two insulated wires 2 and 3 twisted together with needles 8 interposed between the two wires, the ends of the wires terminating into two spring like prongs 9 and 10, adapted to fit into the conducting 65 sleeves 11 and 12 in lamp base 13, the opposite ends continuing through trunk 14, where one wire from each branch is connected to wire 6 and all the other remaining wires connected to wire 7. A suitable covering of paper, 70 fabric or other suitable material is applied over the wires in trunk 14 to present a natural and pleasing appearance.

The pot 5 is composed of a light moldable material such as plaster of Paris, papier 75 maché or similar material, in which the terminals of all wires are imbedded. An ornamental color effect is applied to the pot 5.

An arm 15, properly anchored as indicated at 16 is embedded in the material composing 80 the pot 5, the opposite end of the arm 15 being bent at right angles as indicated at 17 to form a hinged connection in the vacuum cup 18, which is composed of live rubber of the well known conical or spherio-segmental 85 type, having a vertically disposed aperture to receive the pivotal end 17 of arm 15.

The lamp is composed of the ordinary evacuated glass bulb 19 provided with lead-in wires 20 and 21 and filament 22, the lead-in 90 wires being conductively connected to a pair of metal sleeves 11 and 12, imbedded in an insulating base 23, and adapted to receive the prongs 9 and 10 of the branches 4, the glass bulb being fixedly attached to the in- 95 sulating base 23.

The connections are indicated in the wiring diagram, Fig. 3, wires 2 and 3 representing the wires extending through each branch and through trunk 14, 5a and 5b rep- 100

resenting the common connections of each group within the pot 5, which are respectively connected to wires 6 and 7 as indicated, the plug 28 making connection to battery 27 through wire 25 and wire or frame 26.

- The operation of the device is as follows; lamps 29 are applied to the prongs 9 and 10 of all branches 4. The vacuum cup 18 is pressed against an impervious smooth surface 27 through wire 25 and wire or frame 26.
- 10 face forcing the air out of the cup, thereby retaining the cup against the surface to which it is applied, thus supporting the device. Plug 28 is inserted into a receptacle, or wires 6 and 7 connected to a battery, thus lighting the lamps. To remove the device it is but necessary to draw the cup away against the excess air pressure on the outer surface of cup 18.

Having described an operative method of 20 constructing and using the device, it will be noted that changes in arrangement and construction may be resorted to without departing from the spirit or scope of the invention or sacrificing any of the advantages thereof.

25 I claim:

1. A Christmas tree comprising a trunk, a plurality of branches, said branches comprising each, a pair of insulated wires terminating in a pair of resilient prongs, said 30 wires being twisted together and having needles or foliage interposed therebetween, said wires being continuous through and forming the trunk of said tree, one wire of each pair being electrically connected to one 35 terminal connection, the other wire of each pair being electrically connected to form the other terminal connection, and means for connecting said terminals to the opposite terminals of a battery, and a support for said 40 tree.

2. In combination, a plurality of branches, each branch composed of a pair of insulated wires twisted together with interposed needles or foliage, said pair of wires terminating 45 adjacent the end of each branch in a pair of resilient prongs, electric lamps electrically connected to said prongs, a trunk for said branches and composed of the continuous wires of said branches, a covering for said 50 trunk wires, an ornamental support for said trunk, and means for connecting one wire of each branch to one terminal of a battery, the remaining wires being connected to the opposite terminal thereof.

55 3. A Christmas tree comprising a plurality of pairs of insulated wires, each pair being twisted together with interposed needles or foliage, each pair terminating at one end in a pair of resilient prongs, the opposite 60 ends of all wires continuing into and through a common member composing a trunk, a covering for said common member, the wires being so joined as to form two terminals, one wire of each pair constituting one terminal, 65 and the other remaining wires constituting

the other terminal, each pair of wires with interposed needles or foliage constituting a branch, and means for connecting said terminals to a source of electric energy.

In testimony whereof I affix my signature. 70
NICHOLAS A. BECKER.
